ATTORNEY.

UNITED STATES PATENT OFFICE.

IVORY HAZELTON, OF PHILADELPHIA, PENNSYLVANIA.

CAR-COUPING.

SPECIFICATION forming part of Letters Patent No. 477,414, dated June 21, 1892.

Application filed February 23, 1892. Serial No. 422,398. (No model.)

To all whom it may concern:

Be it known that I, IVORY HAZELTON, a citizen of the United States, residing in the city and county of Philadelphia, State of Pennsylvania, have invented a new and useful Improvement in Car-Couplings, which improvement is fully set forth in the following specification and accompanying drawings.

My invention consists of a car-coupling formed of a knuckle which is pivoted on the draw-bar and a locking device of novel construction for controlling said knuckle when in coupling position, as will be hereinafter set forth.

Figure 1 represents a perspective view of a car-coupling embodying my invention. Fig. 2 represents a longitudinal vertical section thereof. Fig. 3 represents a perspective view of another form thereof. Fig. 4 represents a horizontal section thereof.

Similar letters of reference indicate corresponding parts in the several figures.

Referring to the drawings, A designates a draw-head, and B designates a knuckle which is connected therewith by means of the vertical pivot C. The knuckle has an extension or heel D, rearward of its pivot or axis, movable in a horizontal recess in the draw-head, and in the said heel is a vertical slot or groove E, which is adapted to receive a tongue F, the latter being connected with a horizontally-arranged shaft G, which is mounted on the draw-head and provided with a crank-handle H, said draw-head having a shoulder against which the heel is adapted to abut when it enters said draw-head.

The operation is as follows: When the knuckle is in coupling position, as shown in

Figs. 2 and 4, the tongue F is turned so as to enter the slot E, whereby the knuckle is controlled by said tongue and thus locked and the coupling of the cars is effected, the knuckles of opposite cars being engaged, as usual in such cases. When it is desired to uncouple the cars, the tongue is raised or lowered, so that it emerges from the slot E, whereby the knuckle is permitted to swing or turn laterally, as shown illustrated in Figs. 1 and 3, and the disconnection of the engaged knuckles may result, it being evident that the coupling is simple, inexpensive, and reliable in its nature, and one that may be operated in a convenient and safe manner, as is evident.

Having thus described my invention, what I claim as new, and desire to secure by Letters Patent, is—

1. A draw-head having a knuckle pivoted thereto and provided with a horizontal recess, a heel on the rear of said knuckle, adapted to enter said recess and having a vertical slot, a horizontal shaft journaled in said draw-head in rear of said knuckle, a tongue on said shaft entering said vertical recess, and means for operating said shaft, said parts being combined substantially as described.

2. A draw-head, a knuckle having a heel with slot therein, a shaft journaled in said draw-head, having a tongue adapted to enter said slot, and a shoulder on said draw-head, against which said heel is adapted to abut, said parts being combined substantially as described.

IVORY HAZELTON.
